UNITED STATES PATENT OFFICE.

JOHN L. TANNER, OF DALLAS, TEXAS.

DRAFTING IMPLEMENT.

1,402,269.

Specification of Letters Patent.

Patented Jan. 3, 1922.

Application filed September 28, 1920. Serial No. 413,323.

To all whom it may concern:

Be it known that I, JOHN L. TANNER, a citizen of the United States, residing at Dallas, in the county of Dallas and State 5 of Texas, have invented certain new and useful Improvements in Drafting Implements, of which the following is a specification.

This invention relates to new and useful 10 improvements in drafting implements.

The invention has particularly to do with an implement for laying out or plotting curves of different degrees and combining in a single implement the functions of a 15 plurality of implements.

In carrying out the invention I provide a flat plate or member in which a plurality of curved slots is provided. Each slot has two curved longitudinal edges, one of which 20 gives an even degree curve and the other of which produces a curve of a certain scale at a given measurement. For instance the bottom curves of the slot may successively range from one degree; while the top curves 25 may range from $0^{\circ} 30'$ to $12^{\circ} 30'$. This arrangement gives a $30'$ curve at the top of each slot. This implement is particularly useful in plotting railroad alinement. It 30 is also proposed to make a portion at one end of each slot tangent thereto and this is particularly useful in engineering work.

The implement may be provided also with scales and graduations along its margins, but these are not essential elements of the 35 invention.

The invention will be more readily understood from a reading of the following specification and by reference to the accompanying drawings, in which an example of the 40 invention is shown, and wherein:

Fig. 1 is a plan view of an implement constructed in accordance with my invention.

Fig. 2 is an edge view of the same, and 45

Fig. 3 is a cross sectional detail on the line 3-3 of Fig. 1.

In the drawings the numeral 10 designates a flat plate or member which may be made of any suitable material, such as celluloid composition. It is preferable to use a 50 substantially transparent material, but this is not essential.

The plate is provided with a plurality of substantially longitudinal slots 11, each beginning at the left hand margin of the plate 55 and curving downwardly at the right hand end. In Fig. 1 the lower edge 12 of the plate is the bottom and the upper edge 13 is the top. The slots curve toward the bottom.

Each slot has two longitudinal edges or 60 sides 14 and 15, the bottom edges being designated by 14 and the top edges by 15. At the left hand end of each slot a portion 11', tangential to the curve of the slot is provided.

Designations are provided at the left hand end of each slot indicating the degree of the curve represented by the lower edge 14 thereof. In Fig. 1, I have shown thirteen slots and the curves represented range 70 from one degree to thirteen degrees, but this may be varied as is evident. I have also arranged inverted designations under each slot, so that when the plate is inverted the top edges 15 will be nearest to the draftsman and the designations will be readable. 75

In using the implement the draftsman selects the curve which is to be drawn and places the plate 10 so that the tangent portion 11' registers with the line of the drawing to which the curve is to be added. 80 Should the desired curve be eight degrees, the plate is placed so that the portion 11' of the slot having 8° degrees at its end will match along its lower edge with the line of 85 the drawing. The lower edge 14 of the slot will give the desired curve and the draftsman has only to trace along the lower edge of the slot, which acts as a guide. The same procedure is employed for tracing any other 90 curve.

A scale 16 may be placed along the margin at the bottom of the plate and the marginal portions 17 of the other three edges may be used for the graduations of a protractor, or any other measurement or scale. 95 It is preferable to round the corners of the plate so that the plate when made in a small size may be more readily slipped into a coat pocket when used in the field and will not 100 catch on objects on the drafting table.

What I claim, is:

In a drafting implement, an elongated plate having a plurality of slots extending

longitudinally thereof, said slots being longitudinally curved, each slot having a pair of longitudinally curved edges, the edges of each slot having different degrees of curvature, said plate being provided at the corresponding ends of said slots with designa-

tions indicating the degree of curvature of the lower edges of said slots, said plate also having designations indicating the degree of curvature of the upper edges of said slots. 10

In testimony whereof I affix my signature.
JOHN L. TANNER.
